METHOD OF FORMING HAND-OPERATED
STRIKING TOOLS

Ernest O. Estwing, Rockford, Ill., assignor to Estwing Manufacturing Company, Incorporated, Rockford, Ill., a corporation of Illinois

Application November 16, 1950, Serial No. 195,988

6 Claims. (Cl. 76—103)

2

1
This invention relates to the formation of hand operated striking tools such as hammers, hatchets and the like and more particularly to a method for producing that class of tools in which the handle, shank and head are integral one with the other.

Tools of the above character as they have heretofore been made have exhibited a lack of uniformity in quality which, though small in comparison to the number of such tools made and used, is nonetheless undesirable.

I have found through the manufacture of such tools over a period of years in accordance with the method disclosed in my prior U. S. Patent No. 1,669,701, that in spite of all reasonable precautions in manufacture a certain percentage of the tools will, while in use, break in the shank, though on final inspection at the plant they appeared to be perfect. Upon inspection a great share of the breaks appeared first as cracks extending in a direction crosswise of the shank, apparently developing as a result of the vibration and strain occasioned by repeated use of the tool. Through the years it has seemed probable that this breakage resulted from some defect in the tool as it left the factory but rigid inspection and study failed to reveal the cause. Sometimes the breakage would occur shortly after the tool was placed in service while at others it would not occur until the tool had been in severe service over a prolonged period of time.

A solution to the problem has been a difficult matter in part because the cause was unknown. It is not possible, from a practical standpoint, to increase the cross sectional area of the shank without increasing the weight and impairing the balance of the tool the latter of which is an important property of such tools. Furthermore, it seemed apparent that the cross sectional area was adequate when the tool was properly constructed as evidenced by the fact that failure occurred in only a small proportion of the total production.

An important object of the invention is the provision of an improved method of manufacturing tools of the character described capable of producing the same substantially free of the defects heretofore associated therewith.

Another object of the invention is the provision of a method for making tools of the character described wherein faults in physical structure resulting from prior used methods are eliminated from the tool.

A further object is the provision of a method of making tools of the aforesaid character which results in improved grain structure in the vital shank portion of the tool.

A still further object is the provision of a method for making tools of the character described at a more rapid and uniform rate so that the necessary operations may all be performed while the metal is still hot enough to be worked without extensive scale formation.

Another object is the provision of a method for making tools of the character described by which workmen of lesser skill may produce products of the highest quality.

Another important object of the invention is the provision of a method for making a hand striking tool wherein the metal is hot processed during successive shaping operations to provide improved properties in the head and shank by drop forging the head portion of the tool transversely of the head and by rolling the metal of the shank into elongated form to produce the shank and handle.

Further objects will be apparent from the following specification, appended claims and drawings thereof, in which—

Figure 1 shows the forging dies of a drop hammer for performing operations resulting in the structures shown in Figs. 4, 6 and 7 in the formation of a striking tool handle;

Fig. 2 shows a pair of rolls for performing operations on the handle, resulting in the structure shown in Figs. 5;

Fig. 3 shows a series of forging and shearing dies for performing operations hot forming operations on the tool head; and

Figs. 4 through 11 show successive steps in the formation of a hammer in accordance with the invention.

For purposes of illustration I have herein shown and described the method as it applies to the making of an ordinary carpenter's hammer, but it will be understood that the essential steps of the method as defined in the claims are equally applicable to the making of other hand striking tools such as hatchets, picks, and other similar tools where the head and shank of the tool are integral.

Referring to the drawings, Figure 1 shows a pair of mating die plates 10 and 11 which in use are mounted in an ordinary power driven drop hammer not shown. For convenience these die plates have a series of mating cavities for performing a number of operations but if desired each pair of cavities may be on separate plates supported in different machines. The plates have mating cavities 12 formed therein of a shape and size to convert a heated billet 13 (Fig. 4) into workable form. This billet is gripped by a pair of tongs 14 held by an operator.

To produce a shape as shown in Fig. 4, the end

of a heated billet is inserted over the cavity 12 by means of the tongs and the drop hammer is operated to deliver a blow on the hot billet. As the die plates 10 and 11 separate, the work is given a quarter turn, in the same relative position, and the drop hammer is again operated to deliver further blows on the work to produce the shape shown in Fig. 4.

This processed shape comprises an enlarged circular body portion 16, a flattened tongue 17 extending from one face of the body portion, and a reduced neck 18 separating the unused part of the billet from the formed body.

The operator then inserts the tongue 17 between the mating rolls 19 and 20, Fig. 2, which are power driven at a constant speed and in a direction to eject the work placed between them toward the operator. These rolls are secured to the driven shafts 21 and 22 which are geared together so they rotate at the same speed and in the same relationship to each other. These rolls are machined with surface areas having different radii from the axis to form the areas 23 of smaller radius providing a clearance area between the rolls and the areas 24 of the larger radius which provide mating die faces for operating upon the piece being processed. Radial shoulders 25 and 26 define the areas of clearance between the rolls, and the active die faces, and it is necessary that in the rotation of the rolls, the shoulders 25 register with each other at the beginning of an operation.

The faces of areas 24 are machined to provide the circumferential grooves 27, 28 and 29 which extend from the leading shoulders 25 to the trailing shoulders 26. These grooves have the corners rounded where they meet the die face and shoulders 25 and 26, and are of different cross sectional areas. The grooves 27 have the largest cross sectional area, the grooves 28 have a smaller cross sectional area, and the grooves 29 have the smallest cross sectional area. The grooves 29 are provided with depressions 30 at a predetermined distance from the shoulder 25 so that the stem 31 as shown in Fig. 5 has the nub 32 formed thereon, in this groove.

In forming the stem 31 the operator inserts the hot shape shown in Fig. 4 between the rolls 19 and 20 when the areas 23 are contiguous and in line with the mating grooves 27 so that as the rolls rotate, the mating grooves 27 impinge on the tongue 17 adjacent the body portion 16 and roll it to conform with the grooves 27. Meanwhile the operator moves his hands toward him as the processed piece is advanced by the action of the rolls, and when the piece is free from the rolls, the piece is given a quarter turn and again inserted between the rolls in line with grooves 28. Again the grooves 28 engage the piece and swage it down to a size determined by the cross sectional area of these grooves. The operator again moves his hands toward him as the piece is being processed and when the piece is free, he again turns the piece one quarter turn and inserts it between the rolls in line with the grooves 29. Again, as the rolls 19 and 20 rotate, the grooves 29 engage the piece and swage it down to a size which they determine. As the rolls advance, the depressions 30 form the nub 32 on the stem to complete the work piece shown in Fig. 5. The purpose of this nub is to provide extra metal on the stem which is later on formed into a flange on the finished handle to locate a hand grip placed on the handle. However, while it is preferred to provide this nub,

it is not essential as the forming rails 19 and 20 may be separated slightly to allow more metal in the rolled stem 31 which can later be flowed to produce the flange.

To provide for locating the piece as it is inserted between the rolls 19 and 20, stops 33, 34 and 35 are adjustably mounted in a cross member 37. By adjusting the nuts 38 on the threaded stems 39, the proper setting for each of the stops may be had. Each of these stops comprises a guard 40 which is bent U-shaped and welded onto the stem 39.

In processing the piece through the rolls, the operator moves quickly and while he may become very adept at locating the piece, these stops facilitate in locating the work to the proper groove, and also in locating the work upon insertion between the rolls to the proper length of swaging action.

After the structure of Fig. 5 has been completed, the piece, still supported by the tongs is placed between the die plates 10 and 11, over the cavity 41 and the drop hammer is again operated to deliver a blow on the piece and force it into the mating cavities 41 to produce a rough shape as shown in Fig. 6.

The piece is then turned over while being held by the tongs 14 and placed over the lower mating cavity 42 formed in die plate 10. The drop hammer is again operated to shape the piece to conform with the mating cavities 42, the excess metal flowing as a flashing 43 all around the formed piece. This flashing allows flaws and defects which might occur along the edges of the shank or handle to be squeezed out beyond the resultant edges of the shank or handle and minimizes the possibility of a cold shut remaining in a vital spot of the handle. This produces a piece similar to that shown in Fig. 7. In this operation the tool head 44 is formed, the shank 46 has been reduced to its rough shape and size, the flare 47 for the hand grip has been shaped and the handle 48 has been given its I beam shape.

From the cavity 42, the piece is moved to another machine and placed on the form 49 carried by a die plate 50 where the shear 51 carried by the plate 52 trims the flashing 43 from the formed tool as shown in Fig. 8. Thereafter the head is placed in a forming die 53, as shown in Fig. 3, to groove the head in the claw formation. This die is formed in a block 54 which may be secured to the platen of the press, not shown. A block 56 carries a forming tool 57 adapted to engage the head and start the formation of the claws by spreading the metal. This results in the structure shown in Fig. 9.

The tool is then moved to a forming die 58, formed in the block 59 and as the press is operated a slitting and forming tool 60 carried by a block 61 engages the claw end of the head and produces the separated claws. The block 59 is attached to the platen of the press, and the block 61 is carried by the movable head. The tool now resembles that shown in Fig. 10, with the claws 62 extending almost straight from the head.

In the final operation the tool is inverted and placed in the forming die 63, also carried by the frame of the press and a mating die 64 carried by the movable head of the press moves down to bend the claws 62 to a desired shape as shown in Fig. 11.

At this time, the metal has cooled considerably and the tool is allowed to cool, after which it is

ground and polished on the exposed surfaces, and a hand grip is pressed on the handle up to the flare 47 and held in place by a retaining plate as well known in the art.

It will be understood that where the method is applied to the manufacture of other tools such as hatchets, picks or other types of hammers, the die cavities 41 and 42 will have correspondingly different shapes and the final shaping of the head will vary depending upon the shape of the head required for the tool. However, in each case the essential steps will be the same in that the head portion will be produced by hammer forging and the shank and handle portion are produced by rolling the metal.

I have found that tools produced in this way are substantially free from the latent defects heretofore present in a certain proportion of tools made in accordance with prior art practice. While all of the reasons for the improved results produced by this method are not entirely plain, it is my belief that they result primarily from two causes.

In prior art practice the tools were made by drop forging the entire structure including the shank and handle portion. The elongated stem 31 was produced by imparting to the metal a succession of blows in a direction transverse to the axis of the stem to elongate this portion in step fashion. This, in my opinion tended to disrupt and break up the grain structure and thus produce a discontinuity along the length of the shank, whereas such discontinuity is avoided by drop forging the head portion and rolling the shank and handle portion to elongate the grain structure in this area.

The operation of forging the stem 31 also required great skill on the part of the operator in order to keep the reduction as uniform as possible along the length of the stem. However, even with the most skillful operation irregular nubs are formed on the stem. It is my belief that when the stem thus formed is later plastically deformed to shape in the cavities 41 and 42, these nubs occasionally fold over in flattened layers instead of flowing or flattening out into a body of the stem thus producing a flaw undetectable by normal inspection methods.

I claim:

1. The method of rough forming a striking tool, comprising forging one end of a heated billet into a workable form having an enlarged circular head and a tongue extending therefrom, roll forming said tongue by a series of passes into an elongated small cross sectional area stem, forging said enlarged circular head and said elongated stem into a tool form having lateral extensions from said stem for the head of the tool, forging said tool form into a specific tool shape having the excess metal flow as flashing from said tool form and removing said flashing from said tool shape.

2. The method of rough forming a striking tool comprising forging one end of a heated billet into a workable form having an enlarged circular head and a tongue extending therefrom, roll forming said tongue by a series of passes into an elongated small cross sectional area stem, forging said enlarged circular head and said elongated stem into a tool form having lateral extensions from said stem for the head of the tool, forging said tool form into a specific tool shape and causing the excess metal to flow as flashing from said tool form, and thereafter shearing said flashing from said rough tool shape.

3. The method of rough forming a striking tool, comprising forging one end of a heated billet into a workable form having an enlarged circular head and a tongue extending therefrom, hot roll forming said tongue by a series of passes into an elongated small cross sectional area stem, rotating the work one-quarter turn between each of said passes, forging said enlarged circular head and said stem into a tool form, forging said tool form into a specific tool shape and causing the excess metal to flow as flashing from said tool form to wash away minute cold shuts from said tool form and shearing said flashing from said tool shape to present a rough finished tool.

15 4. The method of rough forming a striking tool, comprising forging one end of a heated billet into a workable form having an enlarged circular head and a tongue extending therefrom, hot roll forming said tongue by a series of passes into an elongated small cross sectional area stem, rotating the work one-quarter turn between each of said passes, forming a nub on said stem during the last pass through the rolls, forging said enlarged head and said elongated stem to flow the metal of said circular head transversely to the metal in said stem to form a tool head integrally on said stem, forging said tool form into a specific tool shape and simultaneously causing the excess metal to flow as flashing from said tool shape to flow minute defects from said tool form, and shearing said flashing from said tool shape, all of the aforesaid steps being conducted without reheating of the workpiece.

35 5. The method of rough forming a striking tool, comprising forging one end of a heated billet into a workable form having a predetermined amount of metal therein and having an enlarged circular head and a tongue extending therefrom, hot roll forming said tongue by a series of passes into an elongated small cross sectional area stem, rotating the work one-quarter turn between each of said passes forming a lateral nub on said stem during the last of said passes, forging said enlarged circular head and said elongated stem into a tool form by flowing the metal of said circular head transversely in opposite directions to form a tool head, and flowing the metal in said nub into a flange on said stem, forging said tool form into a specific tool shape having the excess metal flow as flashing from said tool form and shearing said flashing from said tool shape to produce a rough tool, all of the aforesaid steps being conducted on the workpiece in rapid succession and without reheating the same.

55 6. The method of forming a striking tool comprising forging one end of a heated billet in a forming die into a workable form having an amount of metal therein in excess of that required in the tool and having an enlarged circular head and a tongue extending therefrom, hot roll forming said tongue by a series of passes into an elongated small cross sectional area stem, drop forging said enlarged circular head and said elongated stem in a forming die into a tool form by flowing metal in said head transversely with respect to said stem to form a tool head, further forging said tool form in a forming die into a specific tool shape having the excess metal flow as flashing from said tool form, shearing said flashing from said tool shape, and subsequently shaping said head to final shape.
